COTTON PRESS.

No. 284,259.

Patented Sept. 4, 1883.

UNITED STATES PATENT OFFICE.

RANSOM DAVID THOMPSON, OF DUMAS, MISSISSIPPI.

COTTON-PRESS.

SPECIFICATION forming part of Letters Patent No. 284,259, dated September 4, 1883.

Application filed June 28, 1883. (No model.)

To all whom it may concern:

Be it known that I, RANSOM D. THOMPSON, a citizen of the United States, residing at Dumas, in the county of Tippah and State of 5 Mississippi, have invented a new and useful Cotton-Press, of which the following is a specification, reference being had to the accompanying drawings.

This invention relates to baling-presses of 10 that class which are stationary and are provided with a lint-room above, into which the cotton is fed direct from the flue of the gin; and its object is to provide a press possessing superior advantages in point of simplicity, ease, 15 and convenience in operation, durability, and general efficiency.

In the drawings, Figure 1 is a side elevation of my improved press. Fig. 2 is an end elevation of the same. Fig. 3 is a vertical 20 central longitudinal sectional view thereof. Fig. 4 is a vertical transverse sectional view taken through the guides of the feed-screw block on the line $x\ x$, Fig. 1. Fig. 5 is a vertical transverse sectional view taken on the 25 line of the screw-threaded bearing of the feed-screw on the line $y\ y$, Fig. 1. Fig. 6 is a detail transverse sectional view taken through the press-box on the line $z\ z$, Fig. 3. Fig. 7 is a detail view in perspective and in section, illustrating the attachment of the follower to the 30 feed-screw. Fig. 8 is a detail perspective view of the head of one of the feed-screws.

Referring to the drawings, A designates four parallel horizontal longitudinal base-beams, 35 on which is secured a transverse series of sill-beams comprising end sills, B B, and a pair of double inner sills, C C, as shown.

From the inner pair of base-beams, A A, extend perpendicular posts D—four at each 40 side—and on the sills B C, outside the posts D, are placed platforms E E, extending longitudinally. The posts D support longitudinal top beams, F F, on which are laid four transverse sleepers, G, that carry at their outer ends longitudinal brace-beams H H, and on the sleepers G, inside the beams H H, is built the floor I of the lint-room J, a sliding trap-door, K, being arranged in the center of this floor over the press-box. The sides L L of the lint- 45 room, which are preferably formed by the gable-roof, as herein shown, are secured to the

beams H H, and in one of the ends M M of the lint-room is provided an opening, N, to accommodate the exit-flue of the gin, adjoining which latter the press is preferably built. 55

At each end of the press the posts D are connected by transverse horizontal braces O, while the inner posts, D, are connected by double cross-braces P, corresponding to the double sills C. Between these braces O and P 60 at each end of the press are secured longitudinally-disposed guide-tracks Q Q, corresponding guides, R R, being secured between the sills B and C, so that a rectangular guide-box is formed for the sliding block S, through which 65 the feed-screw T turns and by which it is guided. The head U of the feed-screw is formed with notches V, that are arranged to be engaged by a pawl, W, on the block S, to retain the feed-screw in position from reverse 70 movement. The head U is also formed with a circumferential shoulder, X, against which a disk, Y, having a serrated or notched periphery, Z, is secured, the disk being prevented from turning by nibs or projections A², 75 that enter grooves B² in the head U, while the securing-pins C² are driven in these grooves and against the said projections. The inner end, D², of the feed-screw T is screw-threaded, 80 and works through a screw-threaded perforation, E², in a vertically-disposed post, F², that comprises independent half-sections G² G². These sections are arranged in slots H² and I², respectively, in the double sills C C and the double braces P P, and are secured from vertical displacement by cross-pins J², passed through perforations K² in the said sections. The sections can be separated in the slots H² 85 and I² sufficiently to permit the feed-screw to be drawn from its position between them when 90 desired, and they are clamped closely together by wedges L², driven into the slots, and secured to the sections G² by pins M², as shown. The point of the inner end, D², of the feed-screw is formed with a shoulder, N², and with an annular groove, O², and the follower P² is formed with a central perforation, Q², by which it is 95 adjusted over the end D² against the shoulder N², and is secured on the said end by a cross-pin, R², that engages the groove O², by which 100 construction the screw can turn and drive the follower without occasioning any revolution of

the latter in the press-box. By removing the pin R^2 the follower can be readily slipped off the feed-screw.

A lever, S^2 , is provided for operating the feed-screw. The lever is formed with a kerf, T^2 , in its under edge, by which it may be rested over the periphery of the disk Y to form its fulcrum, and it is provided with a pivoted hook-plate or pawl, U^2 , that engages the serrations Z on the disk Y to turn the screw and force the follower into the press-box, the screw being retained from reverse movement by the pawl W on block S . The lever S^2 may be retained in position by a pin, V^2 , engaging its end, and placed in any one of a radial series of perforations or holes, w^2 , in the head of the feed-screw.

The inner beams, $A A$, are provided between the inner posts, $D D$, with transverse grooves X^2 , in which are rested the end supports, Y^2 Y^2 , of the press-box. On the said supports is placed the bottom Z^2 of the press-box, and from the side edges of this bottom project hooks A^3 . The vertical sides B^3 B^3 of the box are also rested on the supports Y^2 , and the top piece, C^3 , is placed on the sides. The portions of the press-box are retained in relative position by rods D^3 , that are engaged in the hooks A^3 , and have hook-shaped top ends, E^3 , that are engaged by top cross-rods, F^3 .

The operation and advantages of my invention will be readily understood and appreciated. It is simple and convenient, and is easy of operation.

35 I claim as my invention—

1. The combination of the horizontal parallel base-beams A , the transverse sill-beams rested on the latter, the vertical posts D , extending from the beams A , the longitudinal top beams, F , supported by the posts D , the sleepers G , the lint-room built on the said sleepers, the press-box centrally located on beams $A A$ between the inner sills, and compressing mechanism arranged between the posts D at each side the press-box and working into the ends of the latter, substantially as and for the purpose set forth.

2. The combination of the frame of the press, a centrally-located press-box, the longitudinally-disposed guide-tracks $Q R$, the post F^2 ,

having screw-threaded perforation E^2 , the sliding block S , operating within the said track, the feed-screw working through this block and having the screw-threaded inner end, the follower working in the press-box, and means 55 for operating the feed-screw, substantially as and for the purpose set forth.

3. The combination of the frame comprising the cross-sills and the vertical posts D , the transverse braces O and P , the longitudinally-disposed guide-tracks $Q R$, the slots H^2 and I^2 , the post F^2 , vertically disposed in these slots and having the screw-threaded perforation E^2 , the block S , sliding in the said track and carrying the pawl, the feed-screw working in the block and having the notches V , and formed with the screw-threaded inner end, the follower secured on this screw-threaded end, and means for operating the feed-screw, substantially as and for the purpose set forth. 70

4. The combination, with the sills $C C$, having the slot H^2 , the cross-braces $P P$, having the slot I^2 , the post F^2 , comprising the independent half sections G^2 , and having the screw-threaded perforation E^2 and the perforations 75 K^2 , the pins J^2 , and the wedges L^2 , of the feed-screw, having the screw-threaded end that works through the perforations E^2 , and carrying the follower, substantially as and for the purpose set forth.

5. The combination, with the feed-screw having the shoulder X , and the grooves B^2 in the head, the serrated disk Y , having projections A^2 , and the securing pins C^2 , of the operating-lever S^2 , having the kerf T^2 , and the 85 hook-plate or pawl U^2 , substantially as and for the purpose set forth.

6. The combination of the base-beams $A A$, having the grooves X^2 , the end supports, Y^2 , rested in these grooves, the sides B^3 , the top 90 piece, C^3 , and the rods D^3 and F^3 , substantially as and for the purpose set forth.

In testimony that I claim the foregoing as my own I have hereunto affixed my signature in presence of two witnesses.

RANSOM DAVID THOMPSON.
